UNITED STATES PATENT OFFICE.

GEORGE E. HATCH, OF BROOKLYN, NEW YORK, ASSIGNOR TO HATCH & CO., OF SAME PLACE.

DESIGN FOR THE ORNAMENTATION OF GLASSWARE.

SPECIFICATION forming part of Design No. 16,952, dated October 26, 1886.

Application filed June 17, 1886. Serial No. 205,493. Term of patent 14 years.

To all whom it may concern:

Be it known that I, GEORGE E. HATCH, of Brooklyn, county of Kings, and State of New York, have invented and produced a new and original Design for the Ornamentation of Glassware, of which the following is a full, clear, and exact description, reference being had to the accompanying drawings, and to the letters of reference marked thereon.

10 My design is for the ornamentation of various articles of glassware, and is illustrated on a dish or plate, as shown in the accompanying drawings, forming part of this specification, wherein—

15 Figure 1 is a top or plan view of a dish embodying my design. Fig. 2 is a side elevation of the same; and Fig. 3, a horizontal section of a fragment, showing the exterior figured surface.

20 In all these figures like letters of reference, wherever they occur, indicate corresponding parts.

The general plan of the dish is circular, as indicated in Fig. 1, the inner surface representing a series of radial prisms or pillars separated by strips or bands of ornamented portions, which lend relief to the prisms or pillars. The dish is provided with angular or V-shaped channels, as at *a a*, upon the exterior, the surfaces of the channels being smooth or plain. These channels radiate from

the central portion, and extend up to the edge or margin. Between the channels are the raised portions or pillars *b b*, the exterior surfaces of which are in small-diamond pattern, 35 as at *c c*. The upper margin of the dish is ornamented with alternate rounded portions, as at *e*, and pointed portions, as at *f*.

I desire it understood that my design is not limited to the ornamentation of any particular article of glassware, but that it is intended for ornamentation of various articles of glassware having the general contour of a dish or plate.

Having now fully described my invention, 45 what I claim as new, and desire to secure by Letters Patent, is—

In a design for the ornamentation of glassware, the dish or article having the exterior V-shaped radiating channels with smooth surfaces, and the radiating bands or raised portions located between the channels and ornamented with the small-diamond work, substantially as shown and described.

In testimony that I claim the foregoing I 55 have hereunto set my hand in the presence of two witnesses:

GEO. E. HATCH.

Witnesses:

JOHN BUCKLER,
WORTH OSGOOD.
